UNITED STATES PATENT OFFICE

165,035

COMBINED DRESS AND SCARF

Mamie Verrand, New York, N. Y.

Application March 21, 1951, Serial No. 14,558

Term of patent 3½ years

(Cl. D3—26)

To all whom it may concern:

Be it known that I, Mamie Verrand, a citizen of the United States, residing in New York city, in the county of New York and State of New York, have invented a new, original, and ornamental Design for a Combined Dress and Scarf, of which the following is a specification, reference being had to the accompanying drawing, forming part thereof.

Fig. 1 is a front view of a combined dress and scarf, showing my new design,

Fig. 2 is the rear view thereof, and

Fig. 3 is a fragmentary front view of the dress with the scarf detached.

I claim:

The ornamental design for a combined dress and scarf, substantially as shown.

MAMIE VERRAND,
